ELECTRICAL LINE CLAMP

Kenneth R. Runde, Lemay, Mo., assignor to James R. Kearney Corporation, St. Louis, Mo., a corporation of Missouri

Application December 5, 1949, Serial No. 131,090

3 Claims. (Cl. 339—246)

1

This invention relates generally to electrical clamps and more specifically to so-called parallel groove, hot line clamps of the type adapted for use in attaching tap connections energized feeder lines, the predominant object of the invention being to provide a clamp of this type which is of such improved construction and arrangement that it is capable of performing its intended function in an improved and more efficient manner than were the clamps heretofore employed for the same purpose.

Fig. 1 is a side elevation of the improved clamp of this invention.

Fig. 2 is a rear elevation of the clamp illustrated in Fig. 1.

Fig. 3 is a front elevation of the clamp illustrated in Fig. 1.

Fig. 4 is a plan view of the clamp illustrated in Fig. 1.

Fig. 5 is an enlarged vertical section taken on line 5—5 of Fig. 4.

Fig. 6 is a plan view of a modified form of the invention.

Fig. 7 is a vertical section taken on line 7—7 of Fig. 6.

In the drawing, wherein are shown for purposes of illustration, merely, two embodiments of the invention, A designates in Figs. 1 to 5, inclusive, the improved clamp generally. The clamp A comprises an upper jaw 1 and a lower jaw 2, said jaws having openings 3 formed therethrough through which the shank portion 4a of a bolt 4 is extended. The upper jaw is provided at its top face with a pair of spaced, upstanding ribs 1a, and a non-circular portion of the bolt shank 4a which is located immediately beneath the head 4b of the bolt is disposed between these ribs, whereby rotation of the bolt is prevented, the lower face of the bolt head contacting with top face portions of said ribs. Mounted on the screwthreaded shank portion 4a of the bolt 4 is a jaw operating member 5 which comprises a tubular portion 5a that is provided with internal screwthreads for screwthreaded engagement with the screwthreads of the bolt shank, said tubular portion 5a having an annular flange 5b at its upper end which engages a spring washer 5c that engages a standard washer 5d, which contacts with the lower jaw 2. Also, the tubular portion of the operating member 5 has an eye portion formed thereon which is adapted to be engaged by a suitable tool when it is desired to rotate said operating member relative to the bolt shank in applying the clamp to an overhead conductor.

The upper jaw 1 is provided with a seat 6 which extends from side to side of said upper jaw at the lower face thereof, and the lower jaw is provided with a seat 7 that is related to the seat 6 of the upper jaw and which extends from

2

side to side of said lower jaw at the upper face thereof, said seats 6 and 7 being movable with the jaws 1 and 2 toward each other to clampingly engage an electrical conductor C extended between said seats. Also, the upper jaw 1 is provided with a seat 8 at its lower face, and the lower jaw 2 is provided with a seat 9 at its upper face which is related to said seat 8 of the upper jaw 1, said seats 8 and 9 being extended from side to side of said jaws. The upper jaw 1 has formed thereon an ear 10 which extends outwardly from said upper jaw, and the lower jaw 2 has formed thereon a similar ear 11, said ears 10 and 11 being provided with apertures formed therethrough through which the elongated shank portion of a bolt 12 is extended. The bolt 12 is provided with a head 12' which is located at the lower end of said bolt and is disposed a considerable distance beneath the ear 11 of the lower jaw 2, and interposed between said ear 11 and the head of the bolt 4 is a coil spring 13. The coil spring 13 is maintained in position under compression with the opposite ends of said coil spring contacting with a washer 13' which contacts with the ear 11 and with the bolt head 4', respectively. Also, the screwthreaded upper portion of the bolt shank has screwthreadedly mounted thereon a nut 14 which engages the upper face of the ear 10 of the upper jaw 1.

The upper jaw 1 has formed thereon at the rear portion thereof a pair of spaced, downwardly projected extensions 15 which are disposed at opposite sides of the ear 10, the ear 11 of the lower jaw 2 being projected through the space between said extensions and opposite edge portions of the ear 11 of the lower jaw 2 contacting with the inner edges of said extensions whereby the ear 11 of the lower jaw is maintained in proper alignment relative to the ear 10 of the upper jaw 1. Also, the upper jaw 1 is provided with opposed, side lugs 16 which extend downwardly from said upper jaw at opposite sides thereof and normally overlap the lower jaw 2, opposed side portions of the lower jaw 2 contacting with the inner faces of said lugs whereby said lower jaw is maintained in proper relation with respect to the upper jaw 1.

In the use of the improved clamp disclosed in Figs. 1 to 5, inclusive, of the drawings, the operating member 5 is adjusted downwardly to a required position and an end portion of a tap wire T, which is to be connected to an overhead feeder line with the aid of the improved clamp, is forced between the seats 8 and 9, the coil spring 13 being additionally compressed by such introduction of the end portion of the tap wire between said seats 8 and 9, and said coil spring serving to force said seats 8 and 9 into tight

tripping engagement with the interposed end portion of the tap wire whereby the tap wire is securely gripped by the rear portions of the jaws 1 and 2 of the clamp. With the forward portions of the jaws 1 and 2 in open positions as a result of downward adjustment of the operating member 5, the clamp is applied to a suitable clamp stick and is elevated to the position of the overhead conductor to which the clamp is to be applied, the forward portion of the upper jaw 1 being passed over the conductor to bring the seat 6 of the upper jaw into contact with an upper portion of the conductor C. The operating member 5 is then rotated with the aid of the clamp stick so as to adjust said operating member upwardly relative to the shank portion of the bolt 4, thereby moving the jaws 1 and 2 toward each other and causing the conductor C to be securely gripped between the seats 6 and 7 of the jaws 1 and 2. It is to be noted that when the operating member 5 is adjusted downwardly, the coil spring 13 tends to move the forward portion of the lower jaw 2 downwardly to its open position with respect to the forward portion of the upper jaw 1 so that the clamp may be conveniently passed onto an overhead conductor, said lower jaw being swung by the force exerted by said coil spring in a pivotal manner about the end portion of the tap wire T, which is disposed between the seats 8 and 9.

Figs. 6 and 7 illustrate a modified form of the present invention according to which the upper jaw 17 and the lower jaw 18 are of substantially greater length than are the upper and lower jaws 1 and 2 of the form of the invention shown in Figs. 1 to 5, inclusive. The clamp of Figs. 6 and 7 is provided with a spaced pair of assemblies for drawing the upper and lower jaws toward each other; that is to say, the clamp of Figs. 6 and 7 is provided with a spaced pair of bolts 19 and each of said bolts has screwthreadedly mounted thereon an operating member 20, the pair of bolt and operating member assemblies of Figs. 6 and 7 functioning just as does the bolt and operating member assembly of Figs. 1 to 5, inclusive, in drawing the jaws of the clamp toward each other. Also, the clamp of Figs. 6 and 7 includes a spaced pair of bolts 21 which correspond with the bolt 12 of Figs. 1 to 5, inclusive, each of said bolts 21 extending through alined apertures 22 formed through ears 23 and 24 formed respectively on the upper jaw 17 and the lower jaw 18 and each bolt 21 having a head 21a at its lower end and a nut 21b at its upper end that engages a portion of the upper jaw 17. Also, a coil spring 26 is arranged in embracing relation with respect to a portion of each bolt 21, the opposite ends of said coil spring engaging the head 21a of the bolt and a washer 27 which embraces the shank of the bolt and contacts with the lower jaw of the clamp.

The clamp shown in Figs. 6 and 7 is provided with a coil spring 28 whose opposite end portions are seated in cavities 29 and 30 formed respectively in the upper jaw 17 and the lower jaw 18. This coil spring 28 is a jaw-separating spring, being maintained under tension between the jaws and serving, when the operating members 20 are adjusted downwardly, to move said jaws apart.

I claim:

1. An electrical clamp comprising an upper jaw, a lower jaw, adjusting means for drawing said jaws toward each other, related conductor seats formed on said upper and lower jaws adjacent to the forward portions of said jaws, relat-

ed conductor seats formed on said upper and lower jaws adjacent to the rear portions of said jaws, extended portions formed on said upper and lower jaws and having alined apertures formed therethrough, an elongated element extended through said apertures for connecting the rear portions of said jaws together, and resilient means comprising a coil spring associated with said elongated element for drawing said rear portions of said jaws toward each other and moving the forward portion of said lower jaw away from the forward portion of said upper jaw, said adjusting means including a bolt which extends between the forward and rear related conductor seats formed on said upper and lower jaws.

2. An electrical clamp comprising an upper jaw, a lower jaw, adjusting means for drawing said jaws toward each other, related conductor seats formed on said upper and lower jaws adjacent to the forward portions of said jaws, related conductor seats formed on said upper and lower jaws adjacent to the rear portions of said jaws, extended portions formed on said upper and lower jaws and having alined apertures formed therethrough, an elongated element extended through said apertures for connecting the rear portions of said jaws together, and resilient means comprising a coil spring associated with said elongated element in embracing relation with respect thereto for drawing said rear portions of said jaws toward each other and moving the forward portion of said lower jaw away from the forward portion of said upper jaw, said adjusting means including a bolt which extends between the forward and rear related conductor seats formed on said upper and lower jaws.

3. An electrical clamp comprising an upper jaw, a lower jaw, adjusting means for drawing said jaws toward each other, related conductor seats formed on said upper and lower jaws adjacent to the forward portions of said jaws, related conductor seats formed on said upper and lower jaws adjacent to the rear portions of said jaws, extended portions formed on said upper and lower jaws and having alined apertures formed therethrough, an elongated element extended through said apertures for connecting the rear portions of said jaws together, and resilient means comprising a coil spring associated with said elongated element in embracing relation with respect thereto for drawing said rear portions of said jaws toward each other, said elongated element being provided with an abutment and said coil spring bearing at its opposite ends against said abutment and against the extended portion of said lower jaw and moving the forward portion of said lower jaw away from the forward portion of said upper jaw, said adjusting means including a bolt which extends between the forward and rear related conductor seats formed on said upper and lower jaws.
